UNITED STATES PATENT OFFICE.

PHILIP MYERS, OF GLEN VIEW, ILLINOIS, ASSIGNOR TO THE TOY TINKERS, INC., OF EVANSTON, ILLINOIS, A CORPORATION OF ILLINOIS.

WHEELED TOY.

Application filed November 18, 1925. Serial No. 69,770.

To all whom it may concern:

Be it known that I, PHILIP MYERS, a citizen of the United States, and residing at Glen View, in the county of Cook and State 5 of Illinois, have invented a new and Improved Wheeled Toy, of which the following is a specification.

My invention relates to toys and in its general objects aims to provide a toy in which a number of the constituent parts 10 can readily be assembled in various groupings and arrangements to make the toy resemble different articles, in which no tools will be required for assembling or disassembling these parts, and in which the interchangeably grouped parts will be held securely in position when assembled.

Furthermore, my invention provides a structural toy particularly adapted for simulating vehicles of various types.

More particularly, my invention provides a toy in which a number of interchangeable parts are adapted to be mounted on a base member in various groupings and positions, 25 in which the base member is arranged for gripping these interchangeable parts in any of their various positions, and in which simple means associated with the base member serve of firmly latching the assembled 30 interchangeable members to the base.

In one of its advantageous applications, my invention particularly lends itself to the production of a wheeled toy in which body blocks may be interchangeably attached to a wheel-carrying chassis for constructing 35 toys simulating various types of vehicles. Hence I am illustrating and describing my invention in connection with a wheeled toy embodiment of the same, although I do not 40 wish to be limited to its use in connection with a base supported by wheels.

In the drawings,

Fig. 1 is an elevation of a wheeled toy embodying my invention and having certain of the interchangeably attachable body blocks grouped so that the resulting toy vehicle simulates an automobile of the sedan type.

Fig. 2 is a plan view of the same.

Figs. 3, 4, and 5 are reduced elevations, similar to Fig. 1, but showing body blocks grouped on the chassis of the vehicle to

make this respectively simulate a street car, a band wagon and a delivery truck.

Fig. 6 is a plan view of the chassis of the 55 toy vehicle with the body blocks detached.

Fig. 7 is a bottom view of the vehicle, with the rear wheels and parts adjacent to them in section.

Fig. 8 is an enlarged transverse vertical 60 section, taken along the line 8-8 of Fig. 1.

Fig. 9 is an enlarged central and longitudinal section taken through the front portion of the toy vehicle of Fig. 2 along the line 9-9 of that figure.

Fig. 10 is an enlarged perspective view of 65 one of the body blocks.

Fig. 11 is a perspective view of the detachable thrust member against which the 70 assembled body blocks are pressed by the spring mounted on the rear of the chassis.

In the illustrated embodiment, my toy is shown in a form in which interchangeably grouped body blocks are disposed behind one another upon a horizontally extending 75 base member which forms the chassis of a toy vehicle, the body blocks (numbered from 1 to 5 inclusive according to their respective sizes and types) being supplied in a sufficient number of each to permit one 80 or more of each to be included in the selected group.

This base member is formed of sheet metal and includes a flat horizontal base 6 having its rear end turned upward to afford 85 a thrust web 7 and having a perforation 8 near its forward end. Connected to the opposite longitudinal edges of the base 1 are a pair of webs 9 which overhang the base 6 and which have their opposed edges spaced 90 by a distance less than the uniform thickness of the body blocks. Each body block is provided on its opposite faces with at least one pair of grooves 10 adapted to be entered respectively by the webs 9, these 95 grooves being parallel to one face of the block and spaced from that face by a distance approximately the distance between the base 6 and the free edge of either of the webs 9, thereby enabling each body block 100 to be slidably engaged by the ward webs (as shown in Fig. 8) when slid along the base from the forward end thereof.

Secured to the rear thrust web 7 is a

compression spring 11 against which the rear member of the row of blocks abuts and which spring presses the row of blocks against a thrust member disposed near the forward end of the base member. This thrust member, as shown in Fig. 11 has a base portion 12 of a width approximately that of the base 6 and hence adapted to have its lateral ends underhang the webs 9, and a riser portion 13 adapted to engage the forward end of the row of body blocks. To secure such a thrust member to the base member, I desirably provide the base portion 12 with a perforation 14 adapted to align with the perforation 8 in the base member and snap through the aligned perforations a pull-hook 15 to which the pull-cord 16 of the vehicle is attached.

All of the body blocks have their dimensions (longitudinally of the grooves in the blocks) a multiple of a given measurement, and the distance (marked 17 in Fig. 6) between the perforation 8 and the forward end of the spring is slightly shorter than a given multiple of that unit, so that the spring will be under compression when the length of the assembled group of blocks corresponds to that given multiple. Thus, in Fig. 1, the smallest block 3 is the unit of measurement; the blocks 2 are of the same length, but twice as high, the block 1 is of double this unit length and height, and the blocks 4 and 5 are each double this unit in length and four times this unit in height, while the normal distance 17 of Fig. 6 is somewhat less than twelve times this unit of length. By thus making the height of certain blocks also a multiple of the same unit of length, I can employ the same blocks also when disposed with either of two faces upright, for which purpose I provide them also with additional grooves 10^a at right angles to the grooves 10 and spaced similar to the latter from adjacent faces of the blocks. To increase the variety of shapes which can be given to the group of blocks, I also desirably vary the shapes of some of these, as for example by including blocks 1 of sector-shaped longitudinal section and by providing blocks 4 with projections 18.

If the toy is to constitute a vehicle, I mount the base 6 on wheels, for which purpose I am picturing the base member as having two pairs of integral downwardly directed ears 19 through each of which pairs of ears a wheel shaft 20 extends, and am showing wheels 21 on these shafts, each wheel being spaced from the adjacent ear by a bushing 22.

By employing a snap-hook 15 both as the pull-hook to which a cord is attached and as a part of the means against which the spring presses the row of blocks, I simplify the toy and make it easy for even a young child to attach and detach the blocks in assembled

positions; and by employing an angle-sectioned thrust member such as that of Fig. 11 as another portion of the thrust means, I prevent the forward block from crawling up on the pull-hook.

However, while I have illustrated and described my invention in a wheeled embodiment including numerous desirable details of construction and arrangement, I do not wish to be limited as to these, since many changes might obviously be made without departing either from the spirit of my invention or from the appended claims.

I claim as my invention:

1. In a toy, a supporting member provided with a pair of opposed webs overhanging the top of the said member, a row of supported members carried by the supporting member and each having oppositely directed grooves respectively entered by the said webs, the supported members being slidably attachable from one end of the supporting member, stop means carried by the base member and engaging one end of the said row of supported members, and detachable thrust means engaging the other end of the said row.

2. In a toy, a supporting member provided with a pair of opposed webs overhanging the top of the said member, a row of supported members carried by the supporting member and each having oppositely directed grooves respectively entered by the said webs, the supported members being slidably attachable from one end of the supporting member, stop means carried by the base member and engaging one end of the said row of supported members, a thrust member detachable from the base member and engaging the other end of the said row, and releasable means for latching the thrust member to the base member.

3. In a toy, a base member comprising a horizontal base having its lateral edges upturned to afford a pair of opposed webs, a row of blocks carried by the base member and laterally guided by the said webs, and two clamping members secured to the base member and respectively engaging the endward faces of the said row of blocks to clamp the said blocks between them, one of the clamping members being yielding and the row of blocks being greater in length than the distance between the clamping members when the blocks are detached from the base.

4. In a toy, a base member comprising a horizontal base having its lateral edges upturned to afford a pair of opposed webs, a row of blocks carried by the base member and laterally guided by the said webs, and two clamping members secured to the base member and respectively engaging the endward faces of the said row of blocks to clamp the said blocks between them, each

block having a pair of grooves in its opposite sides respectively entered by the said webs, the width of each block being a multiple of a common unit of measurement.

5. In a toy, a base member comprising a horizontal base having its lateral edges upturned to afford a pair of opposed webs, a row of blocks carried by the base member and laterally guided by the said webs, and

10 two clamping members secured to the base member and respectively engaging the end-ward faces of the said row of blocks to clamp the said blocks between them, each block having a pair of grooves in its oppo-

15 site sides respectively entered by the said webs, certain of the blocks being of rectangular vertical section longitudinally of the said flanges and being provided with two pairs of grooves extending transversely of

20 each other to permit the said blocks to be engaged by the webs in either of two relative positions of the blocks.

6. In a toy, a supporting member provided with a pair of opposed webs overhanging the

25 top of the said member, a row of supported members seated on the supporting member and each having oppositely directed grooves respectively entered by the said webs, the supported members being slidably attach-

30 able from one end of the supporting member, a compression spring secured at one end to the supporting member and having its other end engaging one end of the row of supported members, a thrust member slid-

35 ably attachable to the supporting member from the aforesaid end thereof, and releasable means connecting the thrust member with the supporting member to prevent a relative sliding thereof.

40 7. In a toy, a supporting member provided with a pair of opposed webs overhanging the top of the said member, a row of supported members seated on the supporting member and each having oppositely di-

45 rected grooves respectively entered by the said webs, the supported members being slidably attachable from one end of the supporting member, a stop carried by the base mem-

50 ber and engaging one end of the said row of supported members, and thrust means en-

55 gaging the other end of the said row, and thrust means including a member detachable from the base member and adapted to have a pull cord attached to the same.

8. A wheeled toy comprising a chassis in-

revolvably connected to the chassis, a stop carried by the chassis and disposed above the top of the said base portion, a row of body blocks provided at their opposite sides with grooves respectively entered by the said webs and disposed with one end of the said row engaging the stop, and thrust means re-60 leasably attached to the chassis and engag-65 ing the other end of the said row.

9. A wheeled toy as per claim 8, in which the thrust means include a snap hook attach-70 able to the chassis and adapted for connec-75 tion to a cord by which the wheeled top may be drawn.

10. A wheeled toy as per claim 8, in which the said base portion has a perforation; and in which the thrust means comprise a thrust 75 member engaging the said other end of the row of body blocks and having a perforation aligned with the perforation in the base portion, and a latching member extending through the said aligned perforations for se-80 curing the thrust member to the said base portion.

11. A wheeled toy as per claim 8, in which the thrust means include a thrust member 85 having one portion seated on the said base portion and underhanging the said webs, and having another portion engaging the said other end of the row of body blocks; the thrust means also including a detach-90 able member latching the first named portion of the thrust member to the said base portion.

12. In a toy, a base member having an upwardly extending stop element at one 95 end, a row of blocks carried by the base member and disposed with one end of the row engaging the stop element, the blocks and the base members having interengaging 100 formations permitting an attaching and detaching of the blocks by a slidable movement thereof longitudinally of the base member, and releasable means interposed between the base member and the other end of the row of blocks for clamping the said row against 105 the stop element.

13. A toy as per claim 12, in which cer-110 tain of the blocks have a plurality of forma- tions interchangeably adapted to serve as part of the said interengaging formations so as to permit these blocks to be interengaged with the base member in either of two positions.

Signed at Evanston, Illinois, November 14th, 1925.

PHILIP MYERS.
